UNITED STATES PATENT OFFICE

126,856

DESIGN FOR A WELL BOMB

Clarence A. Ricou, Shreveport, La.

Application August 10, 1939, Serial No. 86,596

Term of patent 3½ years

To all whom it may concern:

Be it known that I, Clarence A. Ricou, a citizen of the United States, residing at Shreveport, in the Parish of Caddo and State of Louisiana, have invented a new, original, and ornamental Design for a Well Bomb, of which the following is a specification, reference being had to the accompanying drawing, forming part thereof.

Figure 1 is a front elevation of a well bomb showing my new design, a portion being broken away.

Figure 2 is an end elevation.

Figure 3 is a section on line 3—3, Figure 1, taken through one side of the bomb.

The essential features of my design reside in a specific configuration and arrangement of the projections on the outer surface of the well bomb as shown.

I claim:

The ornamental design for a well bomb, as shown and described.

CLARENCE A. RICOU.
